UNITED STATES PATENT OFFICE

LEO J. GRUBMAN, OF BELLE HARBOR, NEW YORK

EYE MOUNTING FOR DOLLS

Application filed January 18, 1927. Serial No. 161,726.

This invention relates to eye mountings for dolls, and has for its primary object to provide a simple and easily applied means for retaining an oscillatory eye setting in supported relation to the front wall of the doll head and with the spaced eye members thereof accurately related to the eye openings in the head wall and which will also permit of the free and unretarded oscillatory motion of the eye members to their open and closed positions.

It is a more particular object of the present improvements to provide suitable means on the wall of the doll head and with respect to which the eye openings are accurately located in the front wall thereof which is adapted to support the eye setting for bodily movement at right angles to the axis of oscillation together with retaining means attached to the head wall adjacent the eye openings and including a part contacting with a part of the eye setting and yielding urging the setting forwardly to hold the eye members in cooperative relation with said supporting means and adjacent to the edges of the eye openings in the head wall.

It is also an additional object of the invention to provide an oscillatory eye setting for dolls having an improved form of weighted pendulum for attachment to the shaft or axis thereof and a simply constructed attaching element or clip which may be easily and quickly applied to rigidly connect said pendulum to the shaft. In a preferable embodiment of the invention, I form this pendulum from a length of small gauge resilient wire bent into U-shape form having its spaced arms connected intermediate of their ends by a suitable weight. The extremities of this wire pendulum by contact with an abutment shoulder on the front wall of the doll head, serve to cushion the movement of the eyes to their open positions, said abutment and the shaft or axis of the eye setting being relatively located so that the weight of the pendulum will have a tendency to prevent casual oscillatory motion of the eye setting while the doll head is disposed in an upright position.

With the above and other objects in view,

the invention consists in the improved eye mounting for dolls and in the form, construction and relative arrangement of its several parts as will be hereinafter more fully described, illustrated in the accompanying drawings, and subsequently incorporated in the subjoined claims. 55

In the drawings, wherein I have disclosed one simple and practical embodiment of the invention, and in which similar reference characters designate corresponding parts throughout the several views,—

Figure 1 is a vertical sectional view through the front wall of a doll head showing the eye setting and the retaining member in their initial assembled positions before final attachment of said member to the head wall; 65

Fig. 2 is a rear elevation with the parts in the relative position shown in Fig. 1; 70

Fig. 3 is a sectional view similar to Fig. 1 showing the relative positions of the eye setting and retaining member after the latter has been attached to the head wall;

Fig. 4 is a rear elevation similar to Fig. 2 75 with the parts in the relative positions of Fig. 3;

Fig. 5 is a horizontal sectional view taken substantially on the line 5—5 of Fig. 3, and

Fig. 6 is a detail perspective view of the 80 clip for attaching the pendulum to the shaft of the eye setting.

In a prior application for patent Serial No. 153,485 filed by me on December 9, 1926, I have disclosed an eye mounting wherein 85 the eye setting and the supporting member therefor are first assembled and arranged within the doll head and the eye members of the setting engaged with the walls of the spaced eye openings and with the shaft or 90 axis engaged upon guiding surfaces of the supporting member. Thereafter a relative lengthwise movement is imparted to said supporting member and the doll head whereby 95 parts of the supporting member are fixedly impaled in the structure of the head wall and the axis of the setting is positioned upon suitably formed bearing seats on the supporting member. My present disclosure differs from the subject matter of this prior application 100

in one important particular in that in the present instance the shaft or axis of the eye setting is not directly supported upon the structure of the doll head and the associated member constitutes merely a retaining means 5 to limit the rearward movement of the setting with respect to the head wall, the position of said member relative to the eye openings being determined by the initial engagement of the spaced eyes in sockets formed 10 in the head wall, said member being provided with the wall impaling means as in my prior construction operative upon the relative lengthwise movement of said member and the 15 doll head whereby the member is securely anchored to the head wall.

In the illustrated embodiment of my present improvements, I have shown a portion of a doll head 5 which may be molded from 20 wood pulp, papier mâché, or other suitable composition material and is provided in its front wall with the usual eye openings, one of which is indicated at 6 and which are arranged in appropriately spaced relation to 25 the other molded facial features of the head wall. The opposite side walls of the head adjacent to the front wall thereof are internally provided with the projections or enlargements indicated at 7 having convex or 30 rounded lateral surfaces in which the horizontal channels or grooves 8 are formed. As will be noted from reference to Figs. 3 and 4 of the drawings, these grooves or channels at their rear ends merge into the surfaces 35 of the projections 7 and at their forward ends terminate in the abrupt angular shoulders 9. These grooves or channels provide a suitable means on opposite sides of the doll head which may be advantageously employed in cutting 40 or piercing the eye openings 6 through the front wall of the doll head by means of a tool such as that disclosed in a second application for patent filed by me Serial No. 141- 207, on October 12, 1926, and whereby said 45 eye openings and the grooves 8 may be very accurately located with relation to each other so that when the eye setting is subsequently positioned in the doll head with the ends of its axis disposed in the grooves 8, the 50 individual eye members will properly seat within the respective eye sockets 6' formed in the head wall whereby the pupils on the surfaces of the eye members will be accurately centered with relation to the eye openings. 55 As will be clearly seen from reference to the drawings, the shaft of the eye setting is of appreciably less diameter than the width of the grooves 8 so that under normal operating conditions, the shaft ends do not rest on the 60 shoulders at the lower sides of these grooves, but the eye setting is sustained in such operative position relative to the doll head solely by reason of contact between the spaced eye members and the lower parts of the concave 65 walls of the eye sockets 6'.

Above the eye openings in the front wall of the doll head, said wall is formed with an internal projection or enlargement 10 thereon having a central vertically disposed groove or channel 11 therein which is open 70 at its rear side and upon the lower edge face of said projection. In vertical alignment with this groove or channel, and at the chin portion of the doll head wall, an internal abutment shoulder indicated at 12 is formed 75 upon said wall. The purpose of this construction will hereafter become apparent.

The eye setting which I have selected for the purpose of illustrating a practical embodiment of my present improvements includes a suitable shaft or axis preferably 80 having a cylindrical central portion 13, cylindrical end portions 14 and the intermediate rectangular portions 15. The cylindrical end portions of said shaft are adapted 85 for engagement in the respective horizontal channels or grooves 8 on the opposite sides of the head wall. These end portions of the shaft extend through openings in the outer sides of the eye members 16, which as 90 herein shown are in the form of hollow shells. The openings in the inner sides of these eye shells are of rectangular form and snugly receive the rectangular portions 15 of the shaft or axis and effectually prevent 95 any turning or rotating movement of the eye members relative to said shaft.

For the purpose of imparting the oscillatory motion to the eye setting, I provide a suitable pendulum, which as herein shown includes a suitable length of small gauge resilient wire which is centrally bent into elongated U-shaped form to provide the spaced parallel legs 17 rigidly connected to each other intermediate of their ends by a suitably formed weight 18. The two legs 17 of said wire pendulum adjacent their point of connection by the bight of the elongated loop are bent to provide angularly related parts 19 and 20 respectively. These parts 19 and 20 are adapted to be engaged upon two adjacent faces of the spaced rectangular parts 15 of the shaft or axis and with the bight portion 21 projecting forwardly from one of said surfaces. The pendulum is fixedly retained in connection with the shaft or axis by means of a stamped sheet metal clip of the form shown in Fig. 6, said clip embodying a sheet metal plate 22 adapted for engagement against the front side of the central cylindrical part 13 of the shaft or axis. This plate at one of its ends is provided with the angularly bent arms 23 to extend rearwardly under the inner ends of the rectangular portions 15 of the shaft, said arms terminating 120 in the hooks 24 adapted for engagement around the respective legs 17 of the pendulum as clearly shown in Figs. 3 and 4 of the drawings. The other end of the plate 22 also terminates in a hook 25 which is engaged 130

over the bight portion 21 of the pendulum wire and projects forwardly and downwardly therefrom. Thus, by means of this metal clip which can be easily and quickly applied, the angular parts 19 and 20 of the pendulum wire may be securely locked to the shaft or axis of the eye setting.

The means for retaining the eye setting in its applied position and yieldingly urging the shaft or axis thereof forwardly in the grooves or channels 8 to hold the respective eye members in close engagement with the surfaces of the eye sockets includes a stamped channel shaped sheet metal member 26, the side flanges of which at one of their ends terminate in longitudinally projecting spurs 27. The other end portions of the said flanges are reduced in width as indicated at 28 and the edges thereof provide guiding surfaces 30 as will be hereinafter referred to. The wider portions of these side flanges are also provided in spaced relation to the spurs 27 with the laterally projecting wings 31 having beveled or inclined edge portions 32. The intermediate body portion of the channel shaped member has a tongue or extension 33 projecting longitudinally beyond the ends of the flange sections 28 and which constitutes a positive stop definitely limiting the rearward movement of the shaft or axis of the eye setting.

To the intermediate part of the channel shaped member and on the inner side thereof at a point adjacent the spurs 27 one end of a leaf spring 34 is fixedly attached. As a convenient means for attaching this spring, I provide the channel shaped member with the spaced parallel slots 35 therein through which the end of the leaf spring may be passed or threaded and its extremity caused to exert a tight bearing pressure against the inner face of the plate. From its attached end, the leaf spring normally extends at an inclination towards the open side of the channel shaped member and the free end thereof projects beyond the stop tongue 33.

In the application of the eye setting to the doll head, said setting and the member 26 are first assembled in substantially the relative positions shown in Fig. 1 of the drawings. Preferably, I mount the member 26 in a relatively stationary position on a suitable tool arm (not shown) extending through the neck of the doll head. The doll head is tilted slightly from the position shown in Fig. 1 of the drawings with respect to the member 26 until the rear flat surfaces of the rectangular parts 15 of the shaft or axis of the eye setting rest upon the spaced guiding surfaces 30 at the inner ends of the flange sections 28 on the member 26. With the eye setting and the member 26 supported in such relative positions, the eye members 16 are engaged with the surfaces of the sockets at the inner sides of the respective eye openings 6 by the proper

manipulation of the doll head and a relative lengthwise movement is then imparted to the doll head and the member 26. In this movement, it will be understood that the shaft or axis of the eye setting will slide along the 70 guiding surfaces 20. It will be noted that the channel shaped member 26 extends into the groove or channel 11 in the projection 10 so that in such relative movement of the parts, the inclined edges 32 of the wings 31 cut into 75 the structure of said projection at the opposite sides of said channel and at the end of such relative movement, the spurs 27 impale themselves in said structure at the upper end of the channel 11. At this time, the rectangular parts of the axis of the eye setting move off of the guiding surfaces 30 and said axis is positioned below the flange sections 28 as seen in Fig. 3 of the drawings. When the head is moved to an upright position, the spring 34 80 at its lower end bearing against the rear side of the central cylindrical part 13 of the shaft will exert a constant forward pressure against the same, thus holding the surfaces of the two eye members 16 in close contact with 85 the surfaces of the eye sockets 6' in the head wall. It will thus be apparent that since the eye members are first engaged in contact with the walls of the eye sockets and the rear side of the shaft or axis of the setting is engaged 90 with the guiding surfaces 30, there is a definite relationship between the anchoring spurs 27 and wings 31 of the member 26 and the eye openings which determines the point of engagement of said anchoring portions of the member 26 with the doll head structure and therefore, the position of the stop tongue or projection 33 of said member relative to the shaft or axis after the latter has moved 95 off of the surfaces 30. After the retaining member 26 has thus been attached, the structure of the projection 11 will expand sufficiently below the lower ends of the wings 31 to securely lock said anchoring member against any possibility of longitudinal displacement from the channel 11 under its own weight. When the doll head is tilted to a 100 definitely inclined position, the axis of the eye setting and the eye members thereon will oscillate freely under the gravity movement of the weight 18 until the bends of the arms 23 of the clip forming the hooks 24 thereon come into contact with the lower ends of the flange sections 28 which provides a stop limiting the oscillating movement of the eyes to 105 their closed positions. In this movement, under the weight of the eye setting, the leaf spring 34 will yield sufficiently to insure a receding movement of the eyes out of such frictional bearing contact with the walls of 110 the eye sockets as would impede or retard their free oscillating motion. When the doll head is returned to its upright position the oscillating movement of the eye setting is reversed under the action of the weight 18 and 115 120 125 130

the eyes assume an open position with respect to the eye openings 6, at which time the lower ends of the legs 17 of the wire pendulum contact against the abutment shoulder 12. As this wire is relatively thin and highly resili-
5 ent, said projecting end portions of the wire legs 17 will yield slightly relative to the weight 18.

As heretofore stated, in this open position 10 of the eye members, the eye setting is supported against bodily vertical displacement by integral parts of the doll head wall, namely, the lower portions of the eye sockets 6'. The grooves 8 merely serve as guiding 15 ways for the ends of the shaft or axis of the eye setting, the lower sides of said grooves acting as stops preventing the complete downward vertical displacement of the eye setting in the event the doll is subjected to a 20 severe jar and enabling the spring 34 to function and urge the eye setting forwardly to again position the eye members in proper cooperative relation with the walls of the respective eye sockets. Therefore, it will be 25 apparent that if desired, in lieu of the grooves 8, the side walls of the doll head might be formed simply with horizontally projecting shoulders similar to the shoulders provided by the lower sides of the grooves 30 8 and above which the ends of the shaft or axis 15 are positioned.

From the foregoing description considered in connection with the accompanying drawings, the construction, manner of application and several advantages of my improved eye mounting will be clearly and fully understood. It will be seen that the member 26 in this case acts solely as a retaining means for the eye setting limiting 35 the relative movement of its shaft or axis in the guiding slots or grooves 8 in the opposite side walls of the doll head and no weight or strain is imposed upon said member 26 such as would have a tendency to 40 lessen the security of its anchorage to the doll head wall. Also it will be apparent that the manner of assemblage of the two parts and the method of attachment in applied relation to the wall of the doll head 45 insures the greatest freedom of oscillatory motion of the eye setting, while at the same time effectively precluding any possibility of such displacement of the eye setting as to cause the eye members thereof to assume an 50 inoperative position relative to the eye sockets upon the walls of which the eye setting is supported. Also by reason of my new pendulum construction and the manner 55 of its attachment to the axis of the eye setting, I eliminate excessive jar or vibration, and since the retaining member 26 carries its own anchoring means whereby it is 60 fixedly secured to the doll head wall, it will 65 be evident that the application of the eye

setting in its proper operative position may be very easily and quickly accomplished.

I have herein disclosed an embodiment of the eye setting which I have found to be highly satisfactory in practical use, and also 70 a form of the retaining member 26 which is simple, inexpensive and affords the desired security in its attachment to the head wall. Nevertheless, it is possible that the essential features of my present disclosure might also 75 be incorporated in various other alternative mechanical structures. Accordingly, it is to be understood that the privilege is reserved of resorting to all such legitimate changes in the form, proportion and relative arrangement of the several elements as may be fairly 80 embodied within the spirit and scope of the invention as claimed.

I claim:

1. In combination, a doll head having horizontal shoulders in its opposite sides adjacent the front wall thereof, an oscillatory eye setting having a shaft positioned with its ends above said shoulders and normally out of contact therewith, and eye members fixed on said shaft movable therewith towards and from the front wall of the doll head, said shoulders limiting downward vertical movement of the setting, and a member fixed to the front wall of the doll head having a part positioned rearwardly of the central portion of the shaft for engagement thereby to constitute a stop limiting the rearward movement of the shaft and the eye members relative to the doll head wall. 85 90 95

2. In combination, a doll head having horizontal shoulders in its opposite sides adjacent the front wall thereof, an oscillatory eye setting having a shaft positioned with its ends above said shoulders and normally out of contact therewith, and eye members fixed on said shaft movable therewith towards and from the front wall of the doll head, said shoulders limiting downward vertical movement of the setting, and additional yieldable means mounted on the doll head wall contacting with the rear side of said shaft to yieldingly resist rearward movement of the shaft and the eye members relative to the front wall of the doll head. 100 105 110 115

3. In combination, a doll head having horizontal shoulders in its opposite sides adjacent the front wall thereof, an oscillatory eye setting having a shaft positioned with its ends above said shoulders and normally out of contact therewith and eye members fixed on said shaft movable therewith towards and from the front wall of the doll head, said shoulders limiting downward vertical movement of the setting, and a spring mounted upon the front wall of the doll head above the eye setting having a depending free end portion contacting with the rear side of said shaft and yieldingly resisting rearward movement of the shaft and the eye members 120 125 130 135

relative to the front wall of the doll head.

4. In combination, a doll head having eye sockets in its front wall, an oscillatory eye setting having a shaft and eye members thereon, means on opposite side walls of the head guiding said shaft at its ends for movement towards and from the front wall of the doll head, a retaining member for the eye setting fixed to the front wall of the doll head above the setting and having a depending part positioned rearwardly of said shaft constituting a stop limiting rearward movement of the shaft and the eye members relative to the front wall of the doll head, and means on said member yieldably coacting with said shaft to urge the same forwardly and hold the eye members in their open positions in close engagement with the surfaces of the eye sockets in the doll head wall.
20. 5. In combination a doll head having eye sockets in its front wall, an oscillatory eye setting having a shaft and eye members thereon, means on opposite side walls of the head guiding said shaft at its ends for movement towards and from the front wall of the doll head, a retaining member for the eye setting fixed to the front wall of the doll head and having a part positioned rearwardly of said shaft constituting a stop limiting rearward movement of the shaft and the eye members relative to the front wall of the doll head, and a spring on said member having a free end interposed between said depending portion of the retaining member and the shaft and yieldably urging said shaft forwardly to hold the eye members in close engagement with the surfaces of the eye sockets in the doll head wall.
6. In combination, a doll head having horizontal grooves in its sides adjacent the front wall thereof and spaced eye sockets in said wall, said grooves being open at their rear ends, an eye setting including a shaft having spaced eye members thereon, said shaft adapted for movement at its ends in said grooves, and means yieldingly urging the shaft forwardly in said grooves to hold the eye members in their open positions in close engagement with the surfaces of the eye sockets in the head wall, and said means yieldingly resisting rearward movement of the shaft and the receding movement of the eye members relative to said eye openings in the oscillatory motion of the eye members.
55. 7. In combination, a doll head having horizontal grooves in its sides adjacent the front wall thereof, said grooves being open at their rear ends, an eye setting including a shaft having spaced eye members thereon, said shaft adapted for movement at its ends in said grooves, and a member fixed to the front wall of the doll head having a part positioned at the rear side of said shaft to retain the eye setting in assembled relation with the doll head and prevent a rearward movement of

the shaft through the open ends of said grooves.

8. In combination, a doll head having horizontal grooves in its sides adjacent the front wall thereof, said grooves being open at their rear ends, an eye setting including a shaft having spaced eye members thereon, said shaft adapted for movement at its ends in said grooves, and means fixed with relation to the doll head having a part positioned rearwardly of the central portion of said shaft and constituting a support therefor to sustain the eye setting in the closed position of the eye members independently of the side walls of the doll head.

9. In combination, a doll head having horizontal grooves in its opposite sides adjacent the front wall thereof and spaced eye sockets in said wall, said grooves being open at their rear ends, an oscillatory eye setting including a shaft and spaced eye members thereon, the ends of said shaft being positioned in said grooves, and a yieldable member mounted upon the front wall of the doll head coacting with said shaft to urge the same forwardly in said grooves and hold the eye members in their open positions in close engagement with the surfaces of the eye sockets, and said member constituting a yieldable bearing for the shaft in the oscillatory motion of the eye members to their closed positions permitting of a simultaneous receding movement of the eye members with respect to the eye sockets.

10. In combination, a doll head having horizontal grooves in its opposite sides adjacent the front wall thereof and spaced eye sockets in said wall, said grooves being open at their rear ends, an oscillatory eye setting including a shaft and spaced eye members thereon, the ends of said shaft being positioned in said grooves whereby the eye setting is sustained upon the side walls of the head when the eye members recede from the sockets, a yieldable member mounted upon the front wall of the doll head coacting with said shaft to urge the same forwardly in said grooves and hold the eye members in their open positions in close engagement with the surfaces of the eye sockets, and said member constituting a yieldable bearing for the shaft in the oscillatory motion of the eye members to their closed positions permitting of a simultaneous receding movement of the eye members with respect to the eye sockets, and additional relatively fixed means positioned in cooperative relation to a part of the eye setting and constituting a positive stop to limit the receding movement of the eye members.

11. In combination, a doll head having spaced eye sockets in its front wall, an oscillatory eye setting including a shaft and spaced eye members thereon, means on opposite sides of the doll head to coact with the shaft at its ends and prevent bodily vertical displacement of the setting from its opera-

tive position while permitting of the bodily rectilinear movement of said shaft and the eye members toward and from the front wall of the doll head, a member having parts embedded in the structure of said head wall to positively fix said member in relation to said wall and the eye setting, said member having a part positioned rearwardly of said shaft and positively limiting the rearward movement of the shaft with respect to said means and the recedent movement of the eye members relative to the eye openings in the oscillatory motion of said members to their closed positions, and means carried by said fixed member and coacting with said shaft to urge said shaft and the eye members forwardly and hold the latter in their open positions in close engagement with the surfaces of the eye sockets in the head wall.

12. In combination, a doll head having internal projections on its opposite sides adjacent the front wall thereof and spaced eye sockets in its front wall, each of said projections having a horizontal shoulder, the front wall of the doll head having an internal projection thereon above the eye openings provided with a vertical channel therein open at its lower end, an eye setting including a shaft and spaced eye members thereon, the ends of said shaft being positioned above said shoulders, a channel shaped retaining member having side flanges provided with anchoring projections and reduced portions for contact with the rear side of said shaft, and a part depending below said flange portions, said retaining member and the doll head with the eyes engaged in the eye sockets adapted for movement relative to each other to embed the projecting parts of said member in the wall structure and secure said member in fixed position within said channel, the shaft of the eye setting being thereby positioned below said reduced portions of the channel flanges and said depending part of the retaining member limiting rearward movement of said shaft, and a leaf spring fixed at one of its ends to said channel member and bearing against the rear side of the shaft to yieldingly urge the same forwardly to hold the eye members in their open positions in close engagement with the surface of the eye sockets.

13. An oscillatory eye setting for dolls comprising a shaft and spaced eye members thereon, a pendulum consisting of an elongated resiliently yieldable U-shaped wire, a weight member connecting the spaced legs of the pendulum intermediate of their ends, and a metal clip engageable with said shaft and with the connected ends of said spaced legs of the pendulum to fixedly connect the shaft and the pendulum with each other.

14. An oscillatory eye setting for dolls comprising a shaft and spaced eye members thereon, a pendulum consisting of an elon-

gated resiliently yieldable U-shaped wire, a weight member connecting the spaced legs of the pendulum intermediate of their ends, said shaft having angularly related surfaces and the connected ends of the pendulum legs having angularly bent portions engaged with said surfaces, and a metal clip engaged with the shaft and having parts coacting with the bight portion of the wire pendulum and the spaced legs thereof to fixedly connect said pendulum to the shaft.

15. An oscillatory eye setting for dolls comprising a shaft and spaced eye members thereon, a pendulum consisting of an elongated resiliently yieldable U-shaped wire, a weight member connecting the spaced legs of the pendulum intermediate of their ends, said shaft having angularly related surfaces and the connected ends of the pendulum legs having angularly bent portions engaged with said surfaces, and a clip having parts engaged with other angularly related surfaces on said shaft and provided with parts adapted to be bent around the spaced legs and the bight portion of the wire pendulum to thereby rigidly connect said pendulum with the shaft.

16. An oscillatory eye setting for dolls comprising a shaft having cylindrical end portions adapted for engagement with suitable supports upon the side walls of a doll head and polygonal shaped intermediate portions, hollow eye members having openings in their opposite sides one of which receives one of the polygonal portions of the shaft to prevent relative rotative movement between the shaft and the eye member, a pendulum consisting of a small gauge resiliently yieldable wire having laterally spaced angular portions engaged with angularly related surfaces of the polygonal portions of the shaft, a metal clip engaged with the shaft and having parts engaged with the pendulum wire to fixedly connect said wire to the shaft, and a weight member fixed upon the pendulum wire in spaced relation to the shaft.

17. In an oscillatory eye setting for dolls, an eye carrying member having angularly related surfaces, a pendulum consisting of a length of resilient wire having angularly bent portions in engagement with said surfaces of said member, a metal clip engaged with said member and having parts engaged with said pendulum wire to fixedly secure the angular portions of said wire to the eye carrying member, and a weight secured to said wire in spaced relation to said member.

18. In an oscillatory eye setting for dolls, an eye carrying member having angularly related surfaces, a pendulum consisting of an elongated resiliently yieldable U-shaped wire, the spaced legs of said wire at their connected ends having angularly bent portions for engagement with said surfaces of said

member, a clip engaged with said member and having parts adapted to be bent around the spaced legs and the bight portion of the pendulum wire to rigidly connect the same with said member, and a weight connecting the spaced legs of said pendulum wire adjacent their other ends.

19. In combination with a doll head having integral supporting means adjacent the eye openings in the front wall of said head and an internal abutment shoulder on the lower portion of said wall; an oscillatory eye setting supported by said means for rectilinear movement towards and from the front wall of the doll head, said eye setting including an eye carrying member, a pendulum consisting of a small gauge resilient wire, means securing said pendulum wire to the eye carrying member, a weight element secured to the wire in spaced relation to one end thereof, said end portion of the pendulum wire adapted to engage the abutment shoulder and yield relatively to the weight in the oscillatory motion of the eyes to open position, and means secured to the doll head wall in cooperative relation with the eye carrying member to limit the rearward bodily movement of the eye setting.

20. In combination, a doll head having eye sockets, an oscillatory eye setting including spaced eye members positioned within said sockets and supporting the setting for oscillatory motion by contact with the socket walls, a member on the head wall having a part positioned rearwardly of the eye setting for engagement by a part thereof to constitute a stop limiting the rearward bodily movement of the setting relative to said sockets, yieldable means interposed between said member and the eye setting coacting with the latter to urge the same forwardly and hold the eye members in close engagement with the walls of the eye sockets, and additional means integrally formed with the wall of the doll head and constituting a stop engageable by parts of the eye setting to prevent downward vertical movement thereof to a permanently displaced position out of operative relation with the eye sockets.

21. In combination with a doll having eye sockets, an oscillatory eye setting including spaced eye members and an axis connecting the same, and means for retaining the eye setting in applied position comprising an elongated member having a longitudinally extending bearing surface intermediate of its ends for contact with the rear side of the axis of the eye setting to hold the eye members in contact with the walls of the respective sockets during a vertical movement of said retaining member, said member at one of its ends being provided with means cooperating with a part on the doll head wall in the vertical movement of said member to rigidly fix said member with respect to the head wall,

and position said bearing surface above the axis of the eye setting, and said member beyond one end of said bearing surface being constructed to provide a part in non-contacting relation to the underside of the axis but providing an abutment rearwardly of the axis to limit lateral rearward movement of the setting which is sustained against vertical movement relative to the front wall of the doll head by contact of the eye members with the walls of the eye sockets.

22. In combination with a doll having eye sockets, an oscillatory eye setting including spaced eye members and an axis connecting the same, and means for retaining the eye setting in applied position comprising an elongated member having a longitudinally extending bearing surface intermediate of its ends for contact with the rear side of the axis of the eye setting to hold the eye members in contact with the walls of the respective sockets during a vertical movement of said retaining member, said member at one of its ends being provided with means cooperating with a part on the doll head wall in the vertical movement of said member to rigidly fix said member with respect to the head wall, and position said bearing surface above the axis of the eye setting, and the other end of said member beyond one end of said bearing surface being constructed to provide a part in non-contacting relation to the underside of the axis but providing an abutment rearwardly of the axis to limit lateral rearward movement of the setting which is sustained against vertical movement relative to the front wall of the doll head by contact of the eye members with the walls of the eye sockets, and a yieldable element interposed between said lower end of the retaining member and the axis of the eye setting to yieldably resist movement of the setting away from the eye sockets during oscillatory motion thereof.

23. In combination with a doll head having eye sockets, an oscillatory eye setting including spaced eye members and an axis connecting the same, and means for retaining the eye setting in applied position comprising an elongated retaining member having means at one of its ends to impale the front wall of the doll head and anchor said member thereto, said member being provided with a longitudinally extending bearing surface to engage the rear side of the axis of the eye setting and hold the eye members in engagement upon the walls of the respective eye sockets during a relative vertical movement of said retaining member to engage the impaling means in the wall structure, said bearing surface being thereby positioned wholly above the axis of the eye setting to release the latter for rearward receding movement relative to the eye sockets, and the other end of said member projecting below said bearing surface and being constructed to provide a part in non-con-

tacting relation to the underside of the axis but providing an abutment rearwardly of the axis to limit such recedent movement, and the eye setting being sustained against vertical movement by contact of the eye members with the walls of the respective eye sockets.

24. In combination with a doll head having eye sockets, an oscillatory eye setting including spaced eye members and an axis connecting the same, and means for retaining the eye setting in applied position comprising an elongated retaining member having means at one of its ends to impale the front wall of the doll head and anchor said member thereto, said member being provided with a longitudinally extending bearing surface to engage the rear side of the axis of the eye setting and hold the eye members in engagement upon the walls of the respective eye sockets

29 during a relative vertical movement of said retaining member to engage the impaling means in the wall structure, said bearing surface being thereby positioned wholly above the axis of the eye setting to release the latter for rearward recedent movement relative to the eye sockets, and the other end of said member projecting below said bearing surface and being constructed to provide a part in non-contacting relation to the underside of

30 the axis but providing an abutment rearwardly of the axis to limit such recedent movement, the eye setting being sustained against vertical movement by contact of the eye members with the walls of the respective

35 eye sockets, and a leaf spring fixed at one of its ends to said retaining member and having its other free end interposed between the rear side of the axis of the eye setting and said lower end of the retaining member to

40 yieldingly cushion the recedent movement of the eye setting.

In testimony that I claim the foregoing as my invention, I have signed my name hereto.
LEO J. GRUBMAN.
